UNITED STATES PATENT OFFICE.

FRANK H. SCHWERIN, OF WEST VIEW, PENNSYLVANIA, ASSIGNOR TO THE DUFF MANUFACTURING COMPANY, OF PITTSBURGH, PENNSYLVANIA, A CORPORATION OF PENNSYLVANIA.

HIGH-SPEED-SCREW JACK.

Application filed August 25, 1923. Serial No. 659,269.

This invention relates to the class of screw lifting jacks known as high-speed jacks having screws of sufficiently steep pitch to run down under the load. Various forms of high-speed jacks are known and the features of the invention are not necessarily limited in their application but are illustrated in connection with the jack disclosed in the Kopf & Schwerin Patent No. 1,329,10 665 of February 3, 1920, for which they have been more particularly designed. The object is, therefore, to provide certain features of improvement whereby greater strength and increased efficiency and convenience are secured.

One of the features is an improved construction of the overrunning clutch between the holding and lowering mechanism and the steep-pitch screw, another feature is an improved construction for the manually operable clutch whereby the lowering means can be coupled with the screw for positive lowering of the jack when without load, and still another feature has to do 25 with an attached lowering handle, which is compactly disposed when not in use.

In the accompanying drawings forming part hereof:

Fig. 1 is a view, partly in elevation and 30 partly in central vertical section of a jack embodying the improvements;

Fig. 2 is a large fragmentary vertical sectional view looking at right angles to Fig. 1, the vertical shaft in the plane of section 35 being shown partly in elevation and partly broken away and in section;

Fig. 3 is a detail view of an operating plunger and cross-pin;

Fig. 4 is an enlarged horizontal section 40 on the line 4—4 of Fig. 1;

Fig. 5 is a fragmentary elevation on an enlarged scale looking at the back of Fig. 1 and showing the lowering handle folded against the frame; and

Fig. 6 is a fragmentary sectional elevation 45 on a still larger scale showing the handle in two positions in full and dotted lines.

The illustrated jack has a hollow base frame 1, with a standard 2 rising therefrom, 50 and a ram or lifting member 3 vertically guided in the hollow standard and having a lifting head 4. A steep-pitch screw 5 is rotatably supported at its lower end in the base frame and rises upward within the

ram 3, which carries a nut or hollow screw member 6 for cooperation with the screw 5. Fastened on the lower portion of the screw is a large spur gear 7, which rests upon ball-plates 8, 9 and interposed balls 10. The gear 7 is meshed by a pinion 11 on the lower end of a vertical shaft 12, which is journaled in bearings 13, 14 and 15 in an annex 16 of the base frame.

Fast on the shaft 12, above the pinion 11, is a bevel gear 17, which may be termed the lifter gear. This gear is meshed by a bevel pinion 18, which, as shown in the Kopf & Schwerin patent referred to, is operated by a long removable bar-lever 19 through oscillatory pawl and ratchet mechanism, 65 which it is not thought necessary to show here in detail since such matters are well known.

A ratchet wheel 20 is fixed to the shaft 70 above the bearing 14, and this is surmounted by a pawl-carrier wheel 21, which is rotatable on the shaft and has depending rim portions 22, which are opposite the periphery of the ratchet wheel. In the intervals 23 between these said portions 22 are pawls 75 24, preferably three in number, pivoted on pins 25 to engage with the teeth of the ratchet wheel, which have sloping backs, so that the two parts of the overrunning clutch thus constituted are free to rotate relatively 80 to each other in one sense or direction while having driving or holding engagement in the reverse sense. One of the features of the invention has to do with this overrunning clutch, which is interposed between 85 the shaft 12, and therefore the screw on the one hand, and the holding and lowering means, to be described, on the other hand.

It will be seen in Fig. 4 that each of the pawls 24 is provided with a tail 26 projecting rearward from its pivot, that is to say reversely to the body of the pawl. The rim portions 22 of the pawl-carrier 21 are formed to allow clearance for these tails, and are provided with sockets 27 in their 90 faces which are opposite the inner sides of the tails. The tails themselves are provided with studs 28 projecting from their inner sides toward said sockets, and compression coil springs 29 are entered in the 95 sockets 27 with their outer ends engaged over the studs 28. These springs constantly 100 depress the pawls so as to bear upon the

ratchet wheel, the construction being such as to avoid the operation of the jack being impaired or destroyed through the failure of the springs of the overrunning clutch.

5 The ends of the bodies of the pawls are preferably formed with two teeth 30, instead of one tooth as heretofore.

The holding and lowering means is preferably, though not necessarily, of the kind 10 comprising a worm wheel 31 meshed by a worm 32, the pitch of the gear being such that the wheel 31 which encircles the shaft 12 can not drive the worm 32. Consequently, if the wheel 31 is connected with the 15 lifting screw, the load can not descend unless the holding worm 32 is rotated in the proper direction. The jack is nevertheless virtually self lowering in the sense that the weight or the load drives the jack down and 20 operates all the mechanism up the holding device 32, which is simply let off by hand. The advantage of this particular form of holding and lowering means is safety, since the jack can not run away or start down 25 unintentionally.

As shown, the worm wheel 31 is united with the pawl-carrier 21, and the arrangement of the overrunning clutch 20, 21, 24 is such that the screw 5 and the shaft 12 30 geared thereto can be operated by the lifting lever 19 for lifting without rotating the worm wheel 31, that is to say independently of the holding and lowering means. At the conclusion of each lifting 35 movement, however, descent is prevented through the positive engagement of the parts of the overrunning clutch so that the effort exerted by the load is transmitted to and resisted by the holding means.

40 The worm 32 occupies a lateral boss or enlargement 33 on the frame annex 16, and its shaft or journals are mounted in suitable bearings, one of which is a gland 34 screwed into the outer end of the boss 33 containing a bearing 35 for the journal end 36. A 45 crank handle 37 constitutes the means for manually rotating the lock or holding device 32, so as to permit the jack to lower. The same handle can also be used for rapidly running the jack up to the load. Heretofore this handle has been a separate piece, adapted to be socketed to the journal end of the worm, and for this reason it has not always been at hand when needed, and in the 50 present improvement an elbow 38 is pinned at 39 to the journal 36 so that its outer portion 40 projects at right angles to its axial portion. The end of the bent portion 40 is bifurcated and receives the inner end 55 of the crank handle proper 37. A pivot pin 41 passed transversely through the parts of this region rigidly connects the handle proper and the elbow for rotary operation, and permits the handle to be folded over 60 the boss 33, where it will be confined by a

lug 37' projecting from the top of the boss 33 near the wall of the annex rising above this boss, as seen in Fig. 5. In the operative position the shank of the handle proper is turned outward, so as to form a continuation of the bent portion 40 of the elbow. Curved notches 42, a quadrant's distance apart on the hub 43 of the handle proper 37, cooperate with a non-positive locking plunger 44 pressed from a bore 45 in the elbow portion 40 by a spring 46, so that the handle is held firmly, though yieldingly, in each of its positions. The folding construction of the crank handle of the lowering worm not only connects the handle permanently to the jack frame, while enabling it to be folded compactly out of the way against the frame, but also has the further advantage that if the handle should be left unfolded while the jack is wheeled about in a rearwardly tilted position, the handle will not become bent or interfere with the wheeling by coming in contact with the ground. It will be seen in Fig. 1 that if the jack should be tilted backward so that 90 the end of the handle bore forcibly against the ground, the pivotal joint 41 would automatically bend in a perfectly safe manner. Were it not for this joint, the handle or the lowering mechanism controlled thereby 95 might easily be injured so as to render one of these large jacks, which are used for jacking up locomotives and heavy cars, either inoperative or unsafe.

While the jack runs down by gravity, as permitted by manipulation of the holding and lowering means, it is nevertheless desirable to provide means for positively lowering or driving down the jack in case the weight of the lifting member 3 alone, when the jack is unloaded, should not be sufficient to overcome friction, or in case at any time sticking might occur when it is desired that the load member shall be set. For this reason means are provided, as in the Kopf & Schwerin patent aforesaid, for positively coupling the rotary holding and lowering mechanism to the shaft 12, and therefore to the screw, in respect to lowering movement when desired. This means includes a normally spring-disengaged and manually-engageable clutch between the holding and lowering means of the shaft 12. Specifically the worm wheel is provided with a crown of ratchet teeth 47, adapted to be engaged by a ring of corresponding teeth 48 on the depending rim of a clutch disk 49, which is engaged with ribs 50 on an upper part of the shaft 12 so as to be movable longitudinally thereon into and out of engagement with the teeth 47 while held against rotation relatively to the shaft. A spring 51, interposed between the clutch member 49 and the worm wheel 31, normally holds the clutch element separated. Thus far the clutch is like that 130

disclosed in the Kopf & Schwerin patent, but improved means are provided for its manual operation.

In the present construction the upper end portion of the shaft is drilled with a longitudinal bore or passage 52, which extends from the upper end to a point within the worm wheel. A transverse bore or passage 53 is also formed in the shaft intersecting the bore 52. An operating button 54 projects at the top of the frame annex 16 and has a stem 55 which passes through an opening in a top plug 56 and downward into the longitudinal passage 52 in the shaft. This stem has a transverse hole through it, through which and through the passage 53 a cross-pin 57 is inserted with its ends projecting at opposite sides of the shaft. The ends of the pin rest upon the top of the longitudinally movable clutch member 51, and the pin is movable transversely to itself in the passage 53, which is considerably larger than the pin. The pin consequently forms the intermediary between the plunger 55 and the clutch member 49, so that downward pressure of the hand upon the button 54 will engage the clutch member 49 with the clutch teeth 47. When the hand is removed, the pressure of the spring 51 automatically raises the clutch member 49 and

the plunger. This construction is very simple and is more serviceable than the construction disclosed in the Kopf & Schwerin patent, wherein the yoke there employed straddling the end of the shaft would sometimes become deranged. The projecting ends of the cross-pin 57 may lie in a circular depression 58 in the top of the clutch member 49, which will prevent endwise displacement of the pin. 35 40

What I claim as new is:

A lifting jack in which there is a steep-pitch lifting screw, a shaft geared to said screw, holding and lowering mechanism and a rotary lowering handle, an automatic overrunning clutch between said mechanism and shaft, and a manually operatable clutch having a spring-disengaged member movable longitudinally of the shaft whereby the lowering means can be coupled to the shaft 50 for positive lowering when desired, characterized by said shaft having intersecting longitudinal transverse passages in its end portion, an operating button having its stem working in the longitudinal passage of the shaft, and a cross-pin movable laterally to itself in the transverse passage and acting as the intermediary between said stem and the manually-operatable clutch member. 55
